UNITED STATES PATENT OFFICE.

EDWARD G. BERDAN, OF CHICAGO, ILLINOIS.

DRIFTING DEVICE FOR LOCOMOTIVES.

1,177,845.

Specification of Letters Patent. Patented Apr. 4, 1916.

Application filed November 23, 1915. Serial No. 62,971.

To all whom it may concern:

Be it known that I, EDWARD G. BERDAN, a citizen of the United States, residing at Chicago, in the county of Cook and State 5 of Illinois, have invented certain new and useful Improvements in Drifting Devices for Locomotives, of which the following is a specification.

My invention relates to drifting devices, 10 and is particularly (although not exclusively) adapted for supplying with steam the cylinders of locomotives when the latter are "drifting."

In engines such as locomotives the lubrication of the pistons which reciprocate within the cylinders is provided for under ordinary operating conditions by oil and by the steam itself which enters the cylinders for the purpose of driving the pistons.

20 In the best practice of locomotive operation the steam which passes to the cylinders is superheated, whereby its temperature and volume (but not its pressure) are greatly increased, thereby resulting in increased 25 economy of operation. When the main supply of steam is cut off from the cylinders, a locomotive will still continue to run by its own inertia. This condition, which also takes place in coasting, is the so-called 30 "drifting." It will be evident that in drifting, inasmuch as steam is not being supplied to the cylinders to assist in their lubrication, the friction of the pistons will rapidly cause a rise in temperature, wear on the 35 parts, and carbonization of the cylinder oil, with very deleterious results, while at the same time the cushioning effect afforded by the steam under normal conditions is eliminated, with consequent danger of accident.

40 This condition is accentuated when super-heated steam of high temperature has been used in the cylinders before drifting takes place.

It is the object of my invention to provide 45 a device which will serve to automatically admit steam, preferably saturated, to the cylinders when drifting takes place, thereby serving to lubricate and cushion the pistons within the cylinders and to prevent the disadvantages which result, as pointed out above, when no adequate lubrication of the cylinders takes place during this period.

50 It is a further object of my invention to interrupt the auxiliary or drifting steam supply to the cylinders when the speed of the locomotive falls below a predetermined

minimum, thereby avoiding waste of steam when the locomotive is at rest or when it is running at low speed, when it is unnecessary to supply drifting steam.

Stated in general terms, my invention consists of a differential piston valve which, under normal conditions, when steam is being supplied to the cylinders through the main steam inlets, is closed, but which is automatically opened when the pressure within the cylinders falls below a predetermined minimum, whereby auxiliary or drifting steam is supplied to the cylinders. The actuation of the differential piston 70 depends on the maintenance of a secondary communication between the cylinder of the differential piston and the main operating cylinders of the locomotive. This secondary communication remains open when the 75 speed of the locomotive is above a predetermined minimum by the actuation of a speed valve, which is operated by any suitable device, as, for example, a pump, which, in turn, is operated from one of the axles 80 or other suitable operating part of the locomotive, so that as long as the locomotive is running in excess of the predetermined minimum speed the speed valve remains open, while if the speed falls below said 85 minimum the speed valve is closed, thereby causing the differential piston to return to its normal position, in which the differential piston valve closes communication between the source of steam and the locomotive cylinders. These and other advantages of my invention will be more readily understood 90 by reference to the accompanying drawings, which show a preferred embodiment of my invention, and in which—

95 Figure 1 is a diagrammatic side elevation of the front portion of a locomotive, showing my drifting device as applied thereto; and Fig. 2 is an enlarged vertical longitudinal section through the main operating 100 parts of my device.

The locomotive diagrammatically represented in Fig. 1 is of the well-known construction. The main steam supply pipe 10 leads from the boiler 11 to the distributing 105 valve chest 12, which contains any suitable type of distributing valve serving to establish communication and to supply steam from the main steam supply pipe 10 to the cylinder 13 within which the main operating piston, of well-known construction, reciprocates. The steam which is supplied to

the main steam supply pipe 10 may be drawn directly from the dome 14 of the locomotive, or a super-heater of well-known construction may be inserted between the dome 14 and the steam supply pipe 10.

An auxiliary steam pipe 15 leads from the "fountain", or other suitable source of steam, from the boiler 11 to the differential cylinder 16, which consists of a circular portion 17, an intermediate portion 18, and a circular portion 19 of greater diameter than the portion 17. As clearly shown in Fig. 2, the auxiliary steam pipe 15 enters the differential cylinder at its intermediate portion 18.

A differential piston is contained within the differential cylinder 16, and consists of the piston head 20 adapted to reciprocate within the portion 17 and piston head 21, of greater diameter than the piston head 20, and adapted to reciprocate within the portion 19 and the piston rods 22 and 23, which serve to connect the piston heads 20 and 21, respectively, with the differential piston valve 24, which serves to normally close the end of the delivery pipe 25 leading from the intermediate portion 18 of the differential cylinder 16 to the distributing valve chest 12. It will be evident that if the connected piston heads 20 and 21 are moved to the left from the position shown in Fig. 2, the differential piston valve 24 will also be moved to the left, whereby the end of the delivery pipe 25 will be uncovered and communication thus established through the differential cylinder 16 between the auxiliary steam pipe 15 and the delivery pipe 25.

The end of the portion 17 of the differential cylinder 16 is closed by the cylinder head 26 containing the vent 27, the purpose of which is to prevent cushioning between the piston head 20 and the cylinder head 26, and to also act as a tell-tale for the leakage of steam past the piston head 20.

The piston head 21 is provided with the port 28, which serves to establish communication between opposite sides of this piston head. The portion 19 of the differential cylinder is closed at its outer end by the cylinder head 29, from which the pipe 30 leads to the upper end of the valve casing 31 of the speed valve 32. The pipe 33 leads from the upper portion of the valve casing 31 to the distributing valve chest 12. When the speed valve 32 is seated, as represented in Fig. 2, it will be evident that communication between pipes 30 and 33 is interrupted.

The speed valve 32 is provided with a valve stem 34, which passes through the bushing 35 permanently located in the lower portion of the valve casing 31. At the lower end of the valve stem 34 is the piston head 36 adapted to reciprocate within the cylinder 37 located within the pump 38. A

helical spring 39 is located between the valve 32 and the bushing 35, and serves to normally hold the valve 32 seated. A port 40 leads to the cylinder 37, within the pump 38. When the pump 38 is operated through the instrumentality of the pulley 41, oil or other fluid is forced through the port 40 into the cylinder 37, and according to the speed at which the pulley is rotated the pressure of fluid within the cylinder 37 correspondingly varies, and thereby varies the distance which the piston head 36 is moved by the pressure of this fluid against the tension of the spring 39. The pulley 41 is connected through a suitable belt 42 with one of the axles 43 of the locomotive. It will be apparent that when the speed of the locomotive exceeds a predetermined minimum the pressure of fluid within the cylinder 37 will be sufficient to move the piston head 36 sufficiently so that the valve 32 is correspondingly unseated to a sufficient extent to afford communication between the pipes 30 and 33.

I have described a well-known form of pump serving as actuating means for the speed valve 32, but it will be apparent to those skilled in the art that any other suitable device which serves to actuate the valve 32 when the speed of the locomotive exceeds a predetermined minimum may readily be used.

By changing the ratio of the pulley 41 to the axle 43, or by changing the tension of the spring 39, it will be apparent that the predetermined minimum speed at which the valve 32 is unseated and communication between pipes 30 and 33 established, may be varied as desired. In practical operation I have found that satisfactory results are obtained when the valve 32 is moved to establish communication between pipes 30 and 33 when the speed of the locomotive exceeds the predetermined minimum of five miles per hour.

Having thus described the various parts used in connection with my invention, the operation of the same may now be readily understood.

When the locomotive is running under normal conditions with open throttle, steam, preferably super-heated to a temperature of 500° to 600° Fahrenheit and usually of a pressure of approximately 175 pounds per square inch, passes through the steam supply pipe 10 into the distributing valve chest 12, from which it is delivered to the cylinder 13, according to the well-known system. The pressure within the steam chest 12 will remain substantially the same as boiler pressure. This steam when introduced into the cylinder of course expands, and serves to drive the piston. During its expansion the pressure of course decreases and the temperature of the steam is correspondingly

lowered. This steam, together with the oil which is introduced into the cylinder 13, serves as lubricant for the same. In the meantime steam at boiler pressure and preferably saturated, but not super-heated, flows from the fountain, or other source connected with the boiler 11, through the auxiliary steam pipe 15 into that portion of the differential cylinder 16 located between the two piston heads 20 and 21. Steam passes through the port 28 of the piston head 21 into the portion 19 of the differential cylinder, and pressure is thereby exerted on the piston head 21, which is of larger size than the piston head 20, so that the differential piston is moved into the position shown in Fig. 2, thereby bringing the differential piston valve 24 over the end of the delivery pipe 25 so that no steam can flow from the auxiliary steam pipe 15 through the delivery pipe 25. If the locomotive is running at a speed greater than a predetermined minimum, as, for example, five miles per hour, the speed valve 32 is unseated so that the pipes 30 and 33 are brought into communication with each other. Since pipe 33 is connected with the distributing valve chest 12, and the pressure in the latter is substantially boiler pressure, no steam can flow from the portion 19 of the differential cylinder 16 through the pipes 30 and 33 to the distributing valve chest. On the other hand, a condition of equilibrium is maintained, and the differential piston having the two piston heads 20 and 21 remains in the position shown in Fig. 2. When the throttle is closed and the supply of steam normally flowing through the steam supply pipe 10 to the distributing valve chest 12 is cut off, and the locomotive is allowed to drift, it will be evident that the pressure within the distributing valve chest 12 will rapidly decrease and a vacuum will be formed, correspondingly reducing the pressure within the cylinder 13 and forming a vacuum therein since no additional steam is being supplied from the main steam supply pipe 10. If this condition were uncorrected, friction of the parts would rapidly cause heating, wear, and carbonization of the cylinder oil. In addition, the lack of steam in the cylinder 13 would eliminate the cushioning effect which is obtained when steam is present in the cylinder. After the pressure in the distributing valve chest 12 has been reduced, and assuming that the locomotive is drifting at a sufficient speed so that the speed valve 32 remains open, steam will flow from the portion 19 of the differential cylinder 16 through pipes 30 and 33 to the distributing valve chest, thereby reducing the pressure in the portion 19 of the differential cylinder. Since this pressure is reduced more rapidly than it can be built up by the flow of steam through the port 28, the pressure of steam to the right of the piston head 21, as indicated in Fig. 2, will cause the differential piston to be moved to the left, thereby unseating the differential piston valve 24 from the end of the delivery pipe 25. Saturated steam will then flow from the auxiliary steam pipe 15 through the portion of the differential cylinder 16 between the piston heads 20 and 21, and thence into the delivery pipe 25, from which it passes into the steam supply pipe 10 and thence to the distributing valve chest 12. From this point the steam is carried into the cylinder 13, and serves to lubricate and cushion the piston within the latter. It will be evident that the steam admitted to the distributing valve chest 12 should not be of a sufficient amount to raise the pressure in the latter to such a point that this steam on its expansion within the cylinder 13 should serve to drive the main operating piston; otherwise, the locomotive would be driven in the same manner as though the throttle had remained open, the steam merely being introduced into the distributing valve chest through another course. As a matter of practice I have found that under ordinary circumstances when the steam pressure within the distributing valve chest 12 does not exceed 25 pounds per square inch, this steam has no practical effect as a means of driving the main operating pistons within the cylinders 13.

In order to insure the maintenance of the steam pressure in the distributing valve chest 12 below a predetermined maximum, as, for example, 25 pounds per square inch, the relations in size between the piston heads 20 and 21 are such that when the pressure within the distributing valve chest exceeds the predetermined maximum, this pressure, being communicated through the pipes 33 and 30 to the portion 19 of the differential cylinder 20, serves to move the piston head 21 to the right, according to the representation shown in Fig. 2, thereby causing the differential piston valve 24 to either partially or wholly cover the delivery pipe 25, so that the amount of steam flowing through the delivery pipe 25 to the steam supply pipe 10 is decreased until the pressure within the distributing valve chest 12 is again brought below the predetermined maximum. It will be evident that when the locomotive is drifting at high speed a much greater amount of steam will be required in the distributing valve chest 12 in order to afford proper lubrication of the cylinder 13. It is by means of the automatic feature which I have just described whereby the pressure of steam within the distributing valve chest 12 is always kept below the predetermined maximum, while at the same time a sufficient amount of steam is allowed to flow to the distributing valve chest 12 in order to afford proper lubrica-

tion, that proper and satisfactory results are obtained for all speeds of drifting. When the speed of the locomotive falls below a predetermined minimum, as, for example, five miles per hour, the valve 32 becomes seated, and communication between pipes 30 and 33 is interrupted. By the flow of steam through the port 28 from the right-hand side of the piston head 21 to the left 10 the pressure on opposite sides of this piston head is equalized, and the latter is thereby moved into the position shown in Fig. 2, so that the differential piston valve 24 is brought to its normal seated position and 15 the further flow of steam to the delivery pipe 25 is stopped. As previously stated, when the locomotive is running at a speed below a predetermined minimum of five miles, for example, the lubrication of 20 the cylinder 13 becomes unnecessary, and by shutting off the supply of auxiliary or drifting steam to the distributing valve chest when the speed is below this predetermined minimum, the danger of wasting 25 the steam when the locomotive is at rest is avoided.

In the foregoing description of my improved drifting device I have mentioned the same as being applied to only one side 30 of the locomotive. It will be apparent that the lubrication afforded by the auxiliary or drifting steam should be applied to the cylinders located on each side of the locomotive, and this result may be attained by a 35 duplication of my drifting device, or by the provision of suitable connecting pipes extending from the delivery pipe 25 and the pipe 33 to the steam supply pipe 10 and the distributing valve chest 12, respectively, 40 located on the opposite side of the locomotive.

It will be apparent to those skilled in the art that many changes could be made in the detailed construction of the parts which I 45 have described without departing from the spirit or scope of my invention, as defined in the appended claims.

What I claim is:

1. A drifting device for engines, comprising the combination of means for supplying steam to the engine cylinder, valve means for normally interrupting the flow of steam through said supply means, means for opening said valve means when the 55 pressure in said engine cylinder is below a predetermined minimum, and means for counter-acting the action of said opening

means when the speed of said engine is below a predetermined minimum, whereby said valve means will be closed. 60

2. A drifting device for locomotives comprising, in combination with a cylinder, a distributing valve chest therefor and a main steam supply pipe leading to said chest, a differential cylinder having a differential 65 piston adapted to operate therein, an auxiliary steam supply pipe leading to said differential cylinder, a delivery pipe communicating with said differential cylinder and said distributing valve chest, a valve 70 operated by said differential piston, said valve normally closing said delivery pipe and thereby interrupting communication between said auxiliary steam supply pipe and said delivery pipe, means for actuating 75 said differential piston and opening said valve when the pressure in said distributing valve chest falls below a predetermined minimum, and means for counter-acting the action of said actuating means when the 80 speed of said locomotive falls below a predetermined minimum, whereby said differential piston will move to its normal position and said valve will close said delivery pipe. 85

3. A drifting device for locomotives comprising, in combination with a cylinder, a distributing valve chest therefor and a main steam supply pipe leading to said chest, a differential cylinder having a differential 90 piston adapted to operate therein, an auxiliary steam supply pipe leading to said differential cylinder, a delivery pipe communicating with said differential cylinder and said distributing valve chest, a valve 95 operated by said differential piston, said valve normally closing said delivery pipe and thereby interrupting communication between said auxiliary steam supply pipe and said delivery pipe, a pipe connecting the 100 larger end of said differential cylinder with said distributing valve chest, whereby said differential piston will be actuated and said valve opened when the pressure in said distributing valve chest falls below a predetermined minimum, a speed valve in said last-mentioned connecting pipe, and means 105 for opening said valve when the speed of said locomotive is above a predetermined minimum. 110

In witness whereof, I hereunto subscribe my name this 20th day of November, A. D. 1915.

EDWARD G. BERDAN.
